UNITED STATES PATENT OFFICE.

GEORGE WALKER, OF NEW BRITAIN, CONNECTICUT.

NAIL-PULLER.

SPECIFICATION forming part of Letters Patent No. 760,715, dated May 24, 1904.

Application filed March 19, 1904. Serial No. 198,979. (No model.)

To all whom it may concern:

Be it known that I, GEORGE WALKER, a citizen of the United States, residing at New Britain, in the county of Hartford and State of Connecticut, have invented certain new and useful Improvements in Nail-Pullers, of which the following is a specification.

My invention relates to improvements in nail-pullers; and the main object of my improvements is efficiency and convenience in operation.

In the accompanying drawings, Figure 1 is a side elevation of my nail-puller. Fig. 2 is a sectional elevation or edge view of the same, the driving-handle being sectioned on the line *xx* of Fig. 1. Fig. 3 is an enlarged transverse section of the driving-handle. Fig. 4 is a side elevation of the lower part of the lever and the two jaws with the jaw-operating lever removed. Fig. 5 is a like view of the same in a slightly-modified form.

A designates the lever, having a straight-sided portion 5 toward its upper end for the driving-handle *B* to slide upon. The said driving-handle is of cast-iron cored out to form a central longitudinal opening 6 of a rectangular form in cross-section, which opening serves as ways or guides for the straight-sided portion 5 of the lever *A*, upon which the said driving-handle is fitted to slide. This opening 6 in the handle for the main portion of its length is intersected by a cross-opening 7, that terminates on each side at the lower end in stop-shoulders 8. The lower end 9 of the driving-handle is rounded off both outside and inside, so that there are no corners at its mouth where the straight-sided portion 5 of the lever *A* enters the said handle. A side orifice 10 is made through the said handle near the upper end of the central longitudinal opening 6 for the insertion of the stop-pin 11, which pin is of a diameter a little less than the width of the cross-opening 7, measured on the longest diameter of the said driving-handle, and also of a length a little less than the dimensions of the said cross-opening measured on the shortest diameter of the said driving-handle, whereby the said pin 11, when properly in place never has any contact whatever with the driving-handle excepting as it

comes in contact with the stop-shoulders 8 to prevent the lever from being pulled out of the driving-handle.

The lower end of the lever *A* is mainly a flattened bar, with a fixed jaw 12 formed integral therewith. It is also provided with a pivot-bearing 13, Fig. 4, for the fulcrum pin or screw 14 of the jaw-operating lever 15 and with a semiboss 16, that is concentric with the said hole 13. The upper half of this boss 16 forms one side of a curved recess for the pivoted jaw 17, the other side of the said recess being formed by the curved wall 18 in the metal of the lever *A*, the said wall, like the edge of the boss 16, being formed concentrically with the said hole 13 for the fulcrum pin or screw. The third side or end of the jaw-recess in the lever *A* is formed by the wall or abutment 19 in the metal of the lever *A*. The pivoted jaw 17 is a flat piece of metal of about the same thickness as the lever *A* and the fixed jaw 12 and is formed with its upper end and inner edge to fit the boss and curved recess of the lever, as shown in Fig. 4. It is also provided with a pin or screw hole 20, Fig. 4, whereby it may be connected with the jaw-operating lever 15 by the employment of a pin or screw 22, Fig. 1, inserted through holes in the said jaw-operating lever and the hole 20 of Fig. 4. The jaw-operating lever 15 has a foot 21 of any ordinary construction, while its other end or main portion is merely slotted longitudinally of a width to receive the lever *A* and pivoted jaw 17. While the pivoted jaw 17 is connected with the operating-lever 15 by means of a single screw, rivet, or pin, it is so guided by the curved boss to which the jaw is fitted that it moves with the operating-lever 15 practically the same as if it was secured thereto by two or more rivets or formed in one piece therewith. When the jaws are fully open, as shown in Figs. 1 and 4, the upper end of the pivoted jaw fits snugly and bears against the walls of the curved recess and abutment in the lever *A*, so that when the jaws are driven into the wood by driving on the said lever no strain whatever is thrown on the pivot-pin of the operating-lever nor on the pin that connects the said lever with the pivoted jaw. The said edges of

the pivoted jaw bearing on the boss 16 and wall 18 of the curved recess cause some friction, so that the said jaw does not move so easily as it would if the pivot was its only bearing; but the said friction instead of being detrimental is believed to be beneficial in that it tends to lessen the pressure of the jaws on the nail and prevents crushing the head. Instead of making the confronting faces of the jaws hooked, as in some nail-pullers, they are so made that when fully opened, as shown, the said faces are nearly parallel to each other, whereby they stand more nearly in longitudinal alinement with the driving-handle to facilitate their entry into the wood.

All of the parts are constructed with especial reference to protecting the hands of the operator by rounded corners and by the absence of any two parts that can possibly come together in such a way as to catch and pinch the skin of the operator's hands.

In the modification shown in Fig. 5 the general construction is the same excepting that the curved wall 18 of Fig. 4 for the outer edge of the pivoted jaw to bear against is omitted.

I claim as my invention—

1. In a nail-puller, the combination of the

lever having the fixed jaw, pivot-bearing, semi-boss concentric with the said bearing and an abutment for the end of the pivoted jaw, with the jaw-operating lever pivoted on the said lever at the said lever-bearing and the pivoted jaw fitted to the said boss and abutment and connected to the said jaw-operating lever for moving therewith.

2. In a nail-puller, the combination of the lever having the fixed jaw, pivot-bearing, semi-boss concentric with the said bearing and a curved recess formed in part by the said boss and in part by the curved wall 18 concentric therewith, and having an abutment at its upper end, with the pivoted jaw 17 fitted to the said boss and recess and substantially of the same thickness as the said lever at the said boss, and a jaw-operating lever slotted to receive the said two jaws and adjacent part of the first-named lever, the said jaw-operating lever being pivoted at the said pivot-bearing and connected with the said pivoted jaw.

GEORGE WALKER.
